RADIATOR FOR SPACE HEATING

Hugh Charles Hebard, Greenford, England, assignor to Aladdin Industries Limited, Greenford, England, a British company

Application September 27, 1947, Serial No. 776,503
In Great Britain November 8, 1946

6 Claims. (Cl. 126—93)

1

This invention relates to heating devices such as domestic radiators of the fixed or portable type and has for its object to provide an improved form thereof capable of being heated by electricity or by combustion gases in such manner that one concentrated heat source at a high temperature is utilised to heat a larger area uniformly at a lower temperature.

According to the invention a heating unit or radiator comprises a casing, a heating element disposed centrally of said casing and capable of being heated to a high temperature, the said heating element being formed in or carried by components of greater area than the heating element and of high heat conductivity and connected at their outer ends or edges to the outer casing which is heat insulated from the central heating element for the purpose of enabling the concentrated central heat source at high temperature to heat a larger area uniformly at a lower temperature.

According to one form of the invention the said heating element is an electrical one and according to another form of the invention the heating element is constituted by a chimney or flue through which combustion gases ascend from a liquid fuel burner.

Reference will now be made to the accompanying drawings which illustrate constructions according to the invention and in which—

Fig. 1 is a front elevation of an electrically heated radiator,

Fig. 2 is a sectional plan taken on the line X—X of Fig. 1,

Fig. 3 is an end elevation of the radiator shown in Fig. 1,

Fig. 4 is a front elevation of an oil burning radiator,

Fig. 5 is a sectional plan taken on the line Y—Y of Fig. 4,

Fig. 6 is an end elevation of the radiator shown in Fig. 4, and

Fig. 7 is an elevation of a constructional detail of the radiator shown in Figs. 4 to 6.

Referring first to Figs. 1 to 3, the radiator comprises an outer casing 1 of sheet metal whose sides are formed with corrugations 2 except for the central portions which are formed to provide a chamber 3 extending throughout the height of the radiator. In the centre of the chamber 3 is disposed an electrical heating element 4 supported between two sheets 5 of metal of high heat conductivity such as aluminium or copper. These metal sheets have central portions 6 which lie close together to form supports for the heat-

2

ing element 4 which is secured in position between them by screws and nuts 7, plates 8 of heat insulating material being mounted externally of the portions 6 of the metal sheets coincident with the heating element. At the ends of the radiator the metal sheets 5 are spaced more widely apart than at the centre as shown in the sectional plan, Fig. 2. The metal sheets 5 are brought into abutting relationship at 9 near their outer ends where they pass through a slot formed between adjacent sections of the end wall 10 of the outer casing 1. The extreme outer ends of the sheets 5 are bent at right angles in opposite directions to form flanges 11 which overlap similar flanges 23 formed on the vertical edges of the two components which form the end wall 10. The joint at each end of the radiator is completed to hold its component portions together by sheet metal members 12 of flattened tubular form with slots 21 in their inner walls which form on each member 12 two inwardly directed portions 13. When the members 12 are caused to slide vertically into the operative positions shown they enclose the flanges 11 and 23 and lock the component parts of the radiator together.

The construction above described provides a small concentrated heating element 4, capable of being heated up to as much as 900° C. which being clamped between the high heat conductivity sheets 5, heats these sheets to a considerable temperature, although a large difference in temperature exists between the point where the heat is applied and the edges of the sheets. As these edges are mechanically connected by the members 11, 12 and 13 to the flanges 23 formed on the ends 10 of the outer casing, heat is transmitted to the outer casing members 1 by conduction from the centre sheets 5. In addition the sheets 1 forming the outer casing are spaced a small distance from the hot centre sheets 5 so that the heat is imparted to the outer casing by radiation across the air gap between the sheets 5 and 1. By this means the temperature of the external casing 1 can be made substantially uniform over the whole of its surface, and the temperature difference between the top and the bottom of the casing is substantially less than usually occurs in radiators of a similar type such as, for instance, those in which water is used as a heat distributing medium. The disposition of the heating element 4 at the centre of the chamber 3 whose walls are spaced farther from the central plane of the radiator than the corrugated walls 2, prevents excessive heating of the central portion of the outer casing which would other-

wise occur due to its proximity to the heating element.

The casing of the radiator illustrated in Figs. 1 to 3 is completed by a cowl 41 and a base 21 which fit around the upper and lower ends respectively of the casing components 1 being held in position by bolts (not shown) whose heads engage means carried on the inner surface of the cowl and whose lower ends project through the base and are engaged by nuts which lock the assembly together. The radiator may be arranged as a fixed or a movable unit. The form illustrated is movable being supported on feet 14 depending from the base 21 and provided with a handle 15 for convenience in moving the radiator from one position to another. For convenience in production, the handle may be omitted for stationary radiators and its points of connection to the cowl closed by studs.

The radiator may also be provided with an external electrical heating element 16 disposed in a framework 17 mounted in a shallow recess 18 in the front wall of the chamber 3. In the base of that chamber are disposed the electrical conductors for the heating element 4 and the conductors and control switch mechanism for the heating element 16 whose operation is controlled by means of an external switch operating arm 19. In the lower casing 21 is a glow light 20 to indicate when the heating element 4 is operative.

The electrical radiator described in connection with Figs. 1 to 3, inclusive, is adapted for use during cool seasons of the year requiring moderate heating effects and in which there are frequently substantial changes in out-of-doors temperature. For mild temperatures, the heating element 4 alone will usually afford satisfactory heating, but for colder periods the additional use of the heating element 16 is found to be desirable. It may further be noted that having the heating element 16 visible from outside of the radiator, produces by its visibly activated condition, a favorable reaction on persons near the radiator, in addition to the heat delivered by the radiator, which particularly in cold weather is of advantage.

The radiator possesses the advantage that it can be very readily assembled or dismantled for inspection or repair. The members 12 are held against unintentional displacement by screws 22 and by removing these screws the said members can be withdrawn vertically whereby the casing members 1 become completely detached from the inner members 5.

The radiator shown in Figs. 4 to 7 is adapted to be heated by a gas or paraffin burner but is constructed otherwise in a manner very similar to the radiator shown in Figs. 1 to 3, and the same reference numerals are used to indicate the cooperating casing components. In place of the electrical heating element, however, the metal sheets 5 are separated at their central portions to form a flue or chimney 24 disposed in axial alignment above a blue flame wick type burner 25 (Fig. 4) mounted upon a fuel reservoir 26. The lower ends of the end walls 10 of the casing are connected by a platform 27 upon which the fuel reservoir is removably mounted and the spaces at the back and front of the radiator between the reservoir and the casing 1 are closed by additional casing components of which the front component 42 is hinged to the centre of casing 1 at 28 so that it can be lifted to enable access to be obtained to the burner for operating a wick adjusting screw 29, to enable the reservoir

to be removed or to effect other necessary operations or adjustments. A spring catch 30 is provided above the hinge 28 to engage the edge of an aperture 31 and hold the hinged component in the raised position when necessary. The aperture 31 normally serves for the observation of the state of the flame above the burner 25. Air is admitted to the base portion 32 above the reservoir through slots 33 in the end plates 10 (see Fig. 6) and is directed to the burner by transverse plates 34 which seal the base of the corrugated portions 2 of the radiator.

At the base of the flue 24 there is provided a floating ring 35 (see Fig. 7) having laterally extending pins 36 movable vertically in slots 37 in a sleeve 38 fixed in the lower end of the flue 24. This ring is adapted to seat upon and position the burner 25 and by the pin and slot arrangement can yield slightly upwards to allow the burner and the reservoir to be withdrawn when refilling is necessary. By the use of the ring 35 an even annular path is ensured around the upper end of the burner for air to support combustion and maintain a draught through the flue. Combustion gases escape through vents 39 near the top of the radiator. This form of radiator may be stationary or mobile, for which latter purpose it can be fitted with castors 40 carried below the platform 27.

The operation of the radiator shown in Figs. 4 to 7 is similar to that of the electrical radiator in that the combustion gases ascending from the burner heat the components 5 from the outer ends of which heat is conducted to the casing components 2 with the addition of heat radiation across the air gaps between the members 5 and 2.

What I claim is:

1. A heating radiator including in combination a sheet metal casing comprising vertical front, back and side heat-radiating walls, a high-temperature heat source disposed centrally in said casing, and vertically disposed metal sheets of high heat conductivity in said casing and spaced from the front and back walls thereof and forming a central compartment containing said heat source, each of said sheets and each of said front and back walls extending from side to side of the radiator, said sheets and said front and back walls having each a large surface area relatively to said heat source, said sheets at their mid-portions having close heat-conductive relation with said heat source and being there widely spaced from said front and back walls, said sheets laterally from their said mid-portions being substantially spaced from each other and being there in close heat-radiating relation with said front and back walls, and said sheets at their lateral edge portions being in heat-conductive engagement with each other and with the lateral edge portions of said side walls, whereby said heat source of small area and high temperature heats said front and back walls to a substantially lower temperature for effectively radiating heat therefrom into a room.

2. A heating radiator including in combination a sheet metal casing comprising vertical front, back and side heat-radiating walls, a high-temperature heat source disposed centrally in said casing, and vertically disposed metal sheets of high heat conductivity in said casing and spaced from the front and back walls thereof and forming a central compartment containing said heat source, each of said sheets and each of said front and back walls extending from side to side of the radiator, said sheets and said front and back

walls having each a large surface area relatively to said heat source, said sheets at their mid-portions having close heat-conductive relation with said heat source and being there widely spaced from said front and back walls, said sheets laterally from their said mid-portions being substantially spaced from each other and being there in close heat-radiating relation with said front and back walls, and said sheets at their lateral edge portions being in heat-conductive engagement with each other and with the lateral edge portions of said side walls, whereby said heat source of small area and high temperature heats said front and back walls to a substantially lower temperature for effectively radiating heat therefrom into a room, each of said side walls being in two parts and in heat conducting relation with said front and back walls, the adjacent vertical edges of said sheets and of said side walls having flanges thereon extending outwardly and away from the junction of said sheets and said walls, and a channel member around said flanges and holding the edge portions of said sheets and said walls together, said member having sliding engagement with said flanges for assembling and disassembling purposes.

3. A heating radiator including in combination a sheet metal casing comprising vertical front, back and side heat-radiating walls, a high-temperature heat source disposed centrally in said casing and vertically disposed metal sheets of high heat conductivity in said casing and spaced from the front and back walls thereof and forming a central compartment containing said heat source, each of said sheets and each of said front and back walls extending from side to side of the radiator, said sheets and said front and back walls having each a large surface area relatively to said heat source, said sheets at their mid-portions having close heat-conductive relation with said heat source and being there widely spaced from said front and back walls, said sheets laterally from their said mid-portions being substantially spaced from each other and being there in close heat-radiating relation with said front and back walls, and said sheets at their lateral edge portions being in heat-conductive engagement with each other and with the lateral edge portions of said side walls, whereby said heat source of small area and high temperature heats said front and back walls to a substantially lower temperature for effectively radiating heat therefrom into a room, said heat source comprising a high-temperature electrical heating unit, and the mid-portions of said sheets comprising a support for said heating unit.

4. A heating radiator including in combination a sheet metal casing comprising vertical front, back and side heat-radiating walls, a high-temperature heat source disposed centrally in said casing, and vertically disposed metal sheets of high heat conductivity in said casing and spaced from the front and back walls thereof and forming a central compartment containing said heat source, each of said sheets and each of said front and back walls extending from side to side of the radiator, said sheets and said front and back walls having each a large surface area relatively to said heat source, said sheets at their mid-portions having close heat-conductive relation with said heat source and being there widely spaced from said front and back walls, said sheets laterally from their said mid-portions being substantially spaced from each other and being there in close heat-radiating relation with said

front and back walls, and said sheets at their lateral edge portions being in heat-conductive engagement with each other and with the lateral edge portions of said side walls, whereby said heat source of small area and high temperature heats said front and back walls to a substantially lower temperature for effectively radiating heat therefrom into a room, said heat source comprising a liquid fuel burner, said sheets having bent portions comprising a central flue for receiving gases of combustion from said burner.

5. A heating radiator including in combination a sheet metal casing comprising vertical front, back and side heat-radiating walls, a high-temperature heat source disposed centrally in said casing, vertically disposed metal sheets of high heat conductivity in said casing and spaced from the front and back walls thereof and forming a central compartment containing said heat source, each of said sheets and each of said front and back walls extending from side to side of the radiator, said sheets and said front and back walls having each a large surface area relatively to said heat source, said sheets at their mid-portions having close heat-conductive relation with said heat source and being there widely spaced from said front and back walls, said sheets laterally from their said mid-portions being substantially spaced from each other and being there in close heat-radiating relation with said front and back walls, and said sheets at their lateral edge portions being in heat-conductive engagement with each other and with the lateral edge portions of said side walls, whereby said heat source of small area and high temperature heats said front and back walls to a substantially lower temperature for effectively radiating heat therefrom into a room, said heat source comprising a liquid fuel burner, said sheets having bent portions comprising a central flue for receiving gases of combustion from said burner, a base below said metal sheets, and a liquid fuel reservoir in said base and supporting said burner.

6. A heating radiator including in combination a sheet metal casing comprising vertical front, back and side heat-radiating walls, a high-temperature heat source disposed centrally in said casing, vertically disposed metal sheets of high heat conductivity in said casing and spaced from the front and back walls thereof and forming a central compartment containing said heat source, each of said sheets and each of said front and back walls extending from side to side of the radiator, said sheets and said front and back walls having each a large surface area relatively to said heat source, said sheets at their mid-portions having close heat-conductive relation with said heat source and being there widely spaced from said front and back walls, said sheets laterally from their said mid-portions being substantially spaced from each other and being there in close heat-radiating relation with said front and back walls, and said sheets at their lateral edge portions being in heat-conductive engagement with each other and with the lateral edge portions of said side walls, whereby said heat source of small area and high temperature heats said front and back walls to a substantially lower temperature for effectively radiating heat therefrom into a room, said front and back walls having vertically extending corrugations, a cowl engaging the upper edges of said front, back and side walls, and a base engaging the lower edges of said walls, thereby forming a totally enclosed

air space in which said sheets are centrally mounted.
